UNITED STATES PATENT OFFICE

2,468,333

ORGANIZATION HAVING ADJUSTABLE
SCREW-THREADED MEMBEREdward L. Johnson, South Orange, N. J., assignor
to The Palmut Company, Irvington, N. J., a
corporation of New Jersey

Application April 26, 1947, Serial No. 744,094

3 Claims. (Cl. 74—424.8)

1

This invention is particularly applicable to adjustable inductance devices used in radio and electronic apparatus, and hence it will be disclosed and discussed in that connection. Embodied within the invention is a locknut organization which may be applied wherever found useful.

As is well known, the inductance of a winding may be varied by varying the telescopic relation between the winding and a ferrous core. Likewise, if there be two inductively coupled windings, e. g. two coaxially superimposed transformer windings, the coupling between the two windings may be varied by varying the telescopic relation between them and a ferrous core which is common to the two windings.

Wohlhieter Patent 2,386,732 discloses an adjustable inductance device in which windings on a tube of fiber or the like are influenced by telescopically adjusting a ferrous core which is positioned within the tube. While this patent shows two transformer windings on the tube, the same arrangement could be used where the tube carried only a single winding, it being desired to vary the inductance of the windings. In the Wohlhieter patent the core is adjusted by means of a threaded stem which is engaged by stationary female thread means, the female thread means being a series of helically disposed spring fingers, of thin sheet metal, which enter the thread of the stem. To hold the stem in adjusted position, the tips of the spring fingers yieldingly engage the root of the thread on the stem in a manner that is well known.

The capacity of the spring fingers to yield outwardly of the axis of the threaded stem is relatively small. Therefore, for the female thread means of the Wohlhieter patent to satisfactorily hold the stem in adjusted position, the actual root diameter of the threaded stem must be quite close to the nominal diameter for which the female thread means is designed. With a die-threaded stem this presents no problem in actual practice. However, most of the threaded stems and other machine screws which are available nowadays, have the threads formed by a rolling procedure. The rolled threads available on the market may vary so much from the nominal size as to cause difficulty when used as in the Wohlhieter patent. Out of a quantity of stems, some may have too tight a fit, and some too loose a fit, in the female thread means.

An object of the present invention is to provide an adjustable inductance device, of the general type disclosed in the Wohlhieter patent, which functions satisfactorily with threaded stems hav-

2

ing size variations of the magnitude that are likely to be found in rolled threads.

Another object of the invention is to provide an adjustable inductance device, or mechanically analogous assembly, in which an undersize threaded stem or screw may be adjusted in female thread means and be automatically held in adjusted position.

An additional object of the invention is to provide an adjustable inductance device, or mechanically analogous assembly, in which an undersize threaded stem or screw may be adjusted in female thread means and be yieldingly engaged thereby to hold the stem or screw in adjusted position.

A further object of the invention is to cause female thread means to yieldingly engage and hold an interengaged male thread which is undersize as compared to the female thread.

A still further object of the invention is to provide a screw threaded assembly in which male threads having substantial variations from the nominal size will be satisfactorily received by the female thread means and be frictionally held against fortuitous rotation.

A still further object of the invention is to provide a screw threaded organization in which a standard male thread is received by standard thread engaging means in the form of thin spring fingers which enter the thread, and the spring fingers are caused to make yielding engagement with the wall surface of the male thread.

Various additional objects and advantages, and objects relating to details and economies of construction, operation and use will be apparent from the detailed description which follows.

My invention is clearly defined in the appended claims. Where parts are, for clarity and convenience, referred to on the basis of their oriented position shown in the accompanying drawing, no limitation as to positioning of the entire structure is to be implied, since it will be understood that the entire structure may be inverted or that it may be used in any inclined position. Also in both the description and the claims, parts at times may be identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawing forming part of this specification, in which:

Fig. 1 is a perspective view showing a stamped

spring metal member which is adapted to support an inductance tube and make threaded engagement with the stem of the core.

Fig. 2 is a vertical sectional view showing the member of Fig. 1 installed in a plate-like section of a radio chassis and mounting an intermediate frequency transformer, or the like, provided with an adjustable iron core.

Fig. 3 is a view similar to Fig. 2 but with the transformer tube, or inductance tube, merely indicated and the core and stem shown in the position which they would assume in the absence of the tube.

Fig. 4 is a greatly enlarged plan view showing in plan the female thread portion, or thread engaging portion, of the member of Fig. 1.

Fig. 5 is a largely diagrammatic sectional view showing a threaded stem, or machine screw, coaxially approaching female thread means such as shown in Fig. 4, the pitch of the male and female threads being related as contemplated by the present invention.

Fig. 6 is a largely diagrammatic view similar to Fig. 5 showing how the male and female threads cooperate.

Fig. 7 is a plane development showing the relationship between the male and female threads.

Referring to Fig. 1, a member designated as a whole by 10 is a stamped one-piece clamp or fastener preferably formed from spring sheet steel, hardened and tempered. It includes a sleeve 11 of generally cylindrical configuration which is longitudinally notched in such fashion as to provide opposed arcuate clamp members 12, 12 and oppositely positioned latch members 13, 13 (see also Figs. 2 and 3). Near their upper ends each vertical edge of the clamp members 12, 12 is provided with a sharp projecting tooth 14. From the upper ends of clamp members 12, 12 wings 15, 15 project outwardly and somewhat downwardly, one wing being provided with a downwardly projecting finger 16. Across the bottom of the sleeve 11 there is a web 17 which is so pierced and stamped as to form inwardly projecting fingers 18 (four shown). These fingers are disposed in thread relationship, the tips of the fingers preferably lying on a helix, and the fingers collectively constituting female thread means which is capable of yielding resiliently.

Referring to Fig. 2, the sleeve 11 is adapted to telescopically receive a fiber tube or the like 20, on which may be wound one or more electrical windings. For example, tube 20 may be provided with a single winding, constituting an inductance. However, as shown schematically in Fig. 2, it may be provided with windings 21 and 22 constituting the primary and secondary of an intermediate frequency radio transformer. For adjusting the inductance of a winding on tube 20, or for varying the coupling of transformer windings on tube 20, there is positioned within the tube a ferrous core 24 fixedly attached to thread stem 25 by means of which the core is telescopically adjustable within the tube 20. The thread of the stem 18 is entered and engaged by the four spring fingers

The clamp 10 with the tube 20 mounted therein is adapted to be received in a mounting hole 23 in a plate 26 which may be a portion of a radio chassis or the like. Upon the assembly being forced downwardly in the hole 23 the wings 15, 15 engage the top of plate 26 and are flexed upwardly, thereby biasing the upper extremities of the clamp members 12, 12 inwardly and causing the clamp members to firmly grip the tube 20.

The finger 16 enters one of two secondary holes 27, 27 in the plate 26 to prevent rotation of the assembly. In the fully seated position shown in Fig. 2 latch members 13, 13 spring outwardly beneath the plate 26, the tips of the latch members engaging the under-surface of the plate and preventing withdrawal of the assembly from the hole 26 unless the latch members 13, 13 be specially retracted for removal of the assembly.

The construction of the clamp of Fig. 1 and assembly of Fig. 2 as thus far described is generally similar to the clamp and assembly disclosed in Wohlhieter Patent 2,386,732, to which reference is made for further disclosure as to details. One difference, however, from the disclosure of the Wohlhieter patent resides in the teeth 14. These are inclined inwardly from the circumference established by arcuate clamp members 12, 12 and they project into the material of tube 20, thereby more firmly anchoring the tube 20 in assembly relationship to the clamp 10. Another difference from the Wohlhieter disclosure is that the pitch of the female thread formed by the teeth 18 is different from the pitch of the male thread of stem 25 as will presently be explained.

Referring to Fig. 4, there is shown in greatly enlarged plan view the center portion of the web 17 of clamp 10. In Fig. 4 the individual teeth of the female thread are designated as 18a, 18b, 18c and 18d. Since the tips of these teeth lie on a helix, tooth 18b will be at a higher level than tooth 18a, as indicated diagrammatically in Fig. 5.

Fig. 5 shows on an enlarged scale a male threaded member 29 such as stem 25, a machine screw, a bolt, or the like. The thread of member 29 has crest 30, root 31 and wall 32. As shown in Fig. 5, the pitch of the thread of screw 29 is greater than the pitch of the thread established by the spring fingers 18a and 18b, i. e. the screw 29 has a lesser number of threads per inch than the number of threads per inch of the female thread established by the fingers 18a-18d of web 17.

When the screw 29 approaches the web 17 in coaxial relation to the female thread thereof, as is assumed in Fig. 5, the screw does not mate with the female thread for, as shown in Fig. 5, if one tooth 18b be in proper relationship to the male thread, then the opposite tooth 18a would project into the space occupied by the material of the screw 29. However, it will be seen that, upon the axis of the screw 29 being canted to the right, the thread thereof will move into such position as to clear the tip of tooth 18a. This condition is shown in Fig. 6, the screw 29 being canted to the right by an amount represented by the angle s . The teeth 18b and 18a now mate with the thread of the screw 29, and the screw is freely rotatable to advance it through the web 17 which contains the teeth 18a and 18b. Fig. 6 shows in dotted lines the position that the teeth 18a and 18b will occupy relative to the screw when the screw has been advanced two turns through the web 17.

The screw 29 having been mated with the female thread, it will be seen from Fig. 6 that if the screw be now forcibly restored to axial relationship with the female thread by eliminating the angle of cant s , tooth 18a will be flexed downwardly and tooth 18b will be flexed upwardly. These teeth will now exert spring pressure upon the wall 32 of the male thread.

The relationship between the male and female threads is shown in plane development in Fig. 7, in which 35 is considered to be the axis of the screw 29 and 36 is considered to be the axis of the female thread of web 17. In developed re-

lationship, the tips of teeth 18a, 18b, 18c and 18d are disposed as shown on dotted lines. The pitch of the thread on screw 29 being greater than the pitch of the female thread established by teeth 18a-18d, the development of one convolution of the helix of the male thread (at the radius at which the tips of the teeth 18a-18d would contact it if they could) is as shown by the line 37. For the teeth 18a-18d to mate with the male thread helix 37, it will be necessary that the axis 35 of the male thread member be tilted to the right sufficiently to eliminate the angle s and bring line 37 into coincidence with the dotted lines 18a-18d.

Fig. 3 illustrates in exaggerated degree the position which screw 25 and core 24 will assume under the influence of the female thread in web 17 when left free to do so. However, due to the yielding nature of thread engaging teeth 18a-18d, the transformer tube 20 may be readily forced into axially aligned position with the axis of the female thread in web 17, to bring the parts into the relationship shown in Fig. 2. While Fig. 3 shows the clamp 10 already installed in the plate 26, the tube 20 of course may be inserted into the clamp 10 before the assembly is mounted in the plate 26, as shown in Fig. 2.

It will be seen that the teeth 18a-18d exert a canting force upon the stem 25 thereby biasing the core 24 into frictional engagement with the wall of the tube 20. This frictional engagement prevents fortuitous rotation of stem 25 and thereby serves to maintain the core 24 in telescopically adjusted position in the tube. Also, tube 20 constitutes a means to limit, even substantially prevent or eliminate, canting movement of the screw in response to the canting force imparted by the female thread. As a result of such limitation on the canting movement of the screw, the fingers of the female thread are flexed and resiliently engage the wall of the male thread. The frictional holding force on the male thread is cumulative with the frictional holding force established between core 24 and the wall of tube 20 to hold the core 24 in adjusted position.

The optimum value of angle s depends upon various circumstances. With relatively small clearance between core 24 and tube 20 (.005" to .008") the angle s may be 2° or 3°. With larger clearances between the core and the tube, a large angle s would be required, in some cases an angle of 5° or 6°. The specific pitches selected for the male and the female thread will also vary with the circumstances and the use to which the invention is put. In some cases I have combined a screw having 32 threads to the inch with a female thread of 44 threads to the inch. Also I have combined a screw having 40 threads to the inch with a female thread of 48 threads to the inch.

While I prefer that the pitch of the screw be greater than the pitch of the female thread, a like result can be obtained where the pitch of the screw is less than that of the female thread. Referring to Fig. 7, and assuming that the pitch of the screw were less than that of the female thread, the line 37 would lie below the line of

teeth 18a-18d. Then by tilting the axis 35 of the screw to the left, the line 37 would be brought into coincidence with the line of teeth 18a-18d. However, the use of a lesser pitch on the screw requires non-standard threads, whereas standard threads may be used where the pitch of the screw is greater than that of the female thread.

A similar result could also be obtained with male and female threads of the same pitch, the clamp 10 being so stamped that the axis of the female thread was tilted with respect to the axis of tube 20. In quantity production, however, this would require special and difficult gaging and inspection procedure.

I claim:

1. In an organization in which a member provided with a male thread is engaged by sheet metal spring fingers which are disposed in thread relationship and enter the male thread, the improvement which comprises the pitch at which the fingers are disposed being less than the pitch of the male thread whereby the fingers exert a canting force on said member, there being means which engages said member and at least limits the canting movement thereof with resultant flexure of the fingers, the fingers thereby resiliently engaging the wall of the male thread and resisting fortuitous rotation of said member, and the engagement between said means and said member also resisting fortuitous rotation of said member.

2. In an organization in which a member provided with a male thread is engaged by sheet metal spring fingers which are disposed in thread relationship and enter the male thread, the improvement which comprises the pitch at which the fingers are disposed being less than the pitch of the male thread whereby the fingers exert a canting force on said member, there being means which engages said member and at least limits the canting movement thereof with resultant flexures of the fingers, the fingers thereby resiliently engaging the wall of the male thread and resisting fortuitous rotation of said member.

3. In an organization in which a member provided with a male thread is engaged by resiliently yieldable female thread means, the improvement which comprises the female thread means having a different pitch from the pitch of the male thread whereby the female thread means exerts a canting force on said member, there being means which engages said member and at least limits the canting movement thereof with resultant yielding of the female thread means, the female thread means thereby resiliently engaging the male thread and resisting fortuitous rotation of said member.
